DESIGN FOR A GLOVE

Wallace E. Meyers, New York, N. Y.

Application November 30, 1937, Serial No. 73,264

Term of patent 7 years

To all whom it may concern:

Be it known that I, Wallace E. Meyers, a citizen of the United States of America, residing in New York city, in the Borough of Manhattan, county and State of New York, have invented a new, original, and ornamental Design for a Glove, of which the following is a specification, reference being had to the accompanying drawing, forming part thereof, wherein

The characteristic feature of my design resides in the extended cheek covering that part of the hand which is immediately adjacent to the wrist.

I claim:

The ornamental design for a glove, substantially as shown and described.

WALLACE E. MEYERS.
